UNITED STATES PATENT OFFICE

HECTOR RABEZZANA, OF FLINT, MICHIGAN, ASSIGNOR TO A C SPARK PLUG COMPANY, OF FLINT, MICHIGAN, A CORPORATION OF MICHIGAN

SPARK PLUG

Application filed October 27, 1922. Serial No. 597,327.

My invention relates to spark plugs designed for use with internal combustion engines to ignite the combustible mixture supplied to the cylinder thereof; and the principal object of my invention is to provide a construction of spark plugs in which the heat to which the same is subjected (which is due in part to the heating action of the burning mixture within the cylinder and in part to the action of the sparks passing between the terminals of the plug) is conducted away from the plug more effectively than has heretofore commonly been the case, thus maintaining the insulating member of the plug at as low a temperature as possible and avoiding injury thereof which would be likely to follow the heating of the same to an abnormally high temperature.

Heretofore spark plugs have commonly included an exterior shell or casing threaded throughout a portion of its length and adapted to be screwed into a threaded opening in a cylinder to thereby fasten the plug in place. In such plugs, however, there is commonly a considerable portion of the shell which is not in contact at all with the cylinder wall and the joint between the parts, which is made up of the threaded portion of the shell and of the opening in which it is screwed, is a joint not well adapted to facilitate the flow of heat from the plug casing to the cylinder wall; which flow must as a matter of course occur before the heat can be dissipated throughout the mass of the cylinder and to the water jacket thereof. My invention obviates this difficulty by very materially increasing the extent of contact between the opening in the cylinder wall and the external metallic shell or casing of the plug and by making a better and more closely fitting joint between the parts; thus on the one hand providing a joint of very materially increased cross section or area, and on the other hand providing a joint in which the parts are in more close and intimate contact with one another than is the case when the plug is screwed into a threaded opening in the engine cylinder.

A further object of my invention is to provide an improved spark plug which may be

more readily put in place and removed from the cylinder than has heretofore commonly been the case; and a still further object is to provide an improved spark plug which may be more readily and cheaply manufactured, and which will be more effective for the purpose for which it is provided, than has heretofore commonly been the case.

The drawing accompanying and forming a part of this specification illustrates the preferred embodiment of my invention; although it will be appreciated that the same may take various other forms than the form illustrated, and that my invention includes such variations and modifications of the particular embodiment thereof illustrated as come within the scope of the concluding claims.

Referring now to the drawing:

Figure 1 is a view of the upper portion of an internal combustion engine cylinder having my improved spark plug fastened in place in the head thereof.

Figure 2 is a fragmentary view upon a considerably larger scale showing my invention in section, and in place within an opening in the cylinder head.

Figure 3 is a view similar to Figure 2 as regards subject matter and scale, but showing a modified form of my invention.

In the drawing, the reference numeral 5 designates an internal combustion engine cylinder within which the piston 6 operates; said cylinder having suitable valves for controlling the supply of combustible mixture to and of exhaust of burned gases therefrom, one of which is indicated by the reference numeral 7. Provided in some appropriate part of the wall of the cylinder as, for example, in the head thereof, is an opening 8 preferably conical in form, and within which my improved spark plug (which as a whole is designated by the reference numeral 9 in Figure 1) is secured; the plug being fastened in place in the opening in any way as, for example, by the use of a bifurcated yoke one end of which straddles the plug and the other end of which bears against the cylinder wall as an abutment; the yoke being held in place relative to the cylinder by means of a stud

bolt 11 and nut 12 upon the free end thereof. My improved spark plug is best shown by itself in Figure 2 of the drawing. The same comprises an external metallic sleeve or casing 13 the periphery of which is tapered to fit the tapered hole provided within the engine cylinder. Within this hollow sleeve or casing an insulating member 14 is secured, said member being illustrated as of a common and conventional form having lower and upper shoulders 15 and 16. The sleeve 13 is provided with an inwardly turned holding flange 17 which overlies the upper shoulder 16 and holds the insulator permanently within the shell; suitable gaskets as shown being commonly interposed between the shoulders and the adjacent surfaces of the sleeve. The holding flange 17 is integral with the sleeve and is formed from a flange at the upper end thereof which is turned inward and into permanent holding engagement with the insulating member 15 in accordance with the usual practice in making single piece spark plugs. The insulating member 14 carries the usual central electrode 18 of the plug, while the outer or grounded electrode 19 is carried by the shell or sleeve 13, as is usual in spark plugs.

The joint between the sleeve 13 and the opening in the cylinder wall in which it fits should be made in such a manner as to secure the best possible and the most intimate contact between the surfaces engaging one another, in order to provide for a free flow of heat from the sleeve 13 outward and into the cylinder wall to thereby dissipate the heat from the insulating member as rapidly as possible and keep its temperature as low as practicable. This intimacy of contact between the parts may be secured in various ways by lapping or grinding the bushing in place within the opening provided for its reception, whereby contact is secured throughout the entire peripheral surface of the sleeve and the adjacent inner wall of the opening. As an alternative scheme the peripheral surface of the bushing may be electroplated with copper or other suitable soft metal, as indicated at 20; or a thin conical bushing of soft metal may be interposed between the parts; the packing metal or gasket in either case being of such softness that it will flow slightly under pressure as the plug is fastened in place and thus fill up all interstices between the casing and the adjacent surface of the cylinder wall. As a further alternative plan for securing an intimate joint between the parts the meeting surfaces of the sleeve and the cylinder wall, or one of them, may be coated with a mercury amalgam which, when the casing is forced into place, will provide a most intimate contact between the parts.

From the foregoing it will be appreciated that in all cases the principal end and aim 65 is to provide a joint between the compara-

tively massive plug casing 13 and the adjacent cylinder wall which will be of as great area as possible, and which will be of such a character as to offer as little resistance as possible to the flow of heat across the joint in question. This provides for a more rapid dissipation of heat from the plug and into the cylinder wall than has heretofore commonly been secured; the result being that the insulating member of the plug remains at a much lower temperature than would be the case if the joint between the plug and the cylinder was of such a character as to impede the flow of heat from the plug. 70 75

In the modified form of my invention 80 shown in Figure 3 the plug 9 fits within an external sleeve 21 in precisely the same manner as hereinbefore explained, the sleeve, however, being a member which is separate from the cylinder wall. In this form of my invention the threaded connection between the sleeve and the cylinder wall will as a matter of course offer more resistance to the flow of heat than a continuous mass of metal, but on the other hand this sleeve may be 85 made of a metal having properties such that a more intimate contact may be provided between it and the casing 13 of the plug than between said casing and the cast metal from which cylinders are commonly made. It 90 therefore follows that what may be lost by the threaded joint will be gained by the possibility of securing more intimate contact between the plug casing and the sleeve and, inasmuch as the sleeve remains permanently 95 in place in the cylinder wall, it may be made of such size as to screw into the threaded opening provided for it with extreme tightness, thus providing a joint in which the parts are in much more intimate contact than is the case in an ordinary threaded joint or connection. 100 105

It will be appreciated that in both and other equivalent forms of my invention the casing of the plug fits within the conical opening provided for its reception throughout substantially the entire length of the casing, thus providing a joint of much greater area between the cylinder wall and the casing than has heretofore commonly been the case. This increase in area at the joint will as a matter of course materially lower the resistance to the flow of heat from the plug to the cylinder wall across the joint, and contributes to 110 the principal end and aim of my invention above set forth, that is, to the provision of a scheme whereby the resistance to the flow of heat outward from the plug is reduced to a minimum; while the specific character of the 115 meeting surfaces at the joint whereby intimacy of contact above that heretofore attained is secured, further contributes to the objects to be attained by my invention. 120 125

Having thus described and explained my 130

invention, I claim and desire to secure by Letters Patent:

1. In combination with a cylinder wall having a tapered opening therein, and the wall of which opening is smooth throughout substantially its entire extent; a smooth and unthreaded metallic shell or casing tapering in form to correspond with said opening, and the length of which is as great as the length of said opening; a yoke member one end of which engages said shell, and the other end of which engages a fixed abutment; a bolt intermediate the ends of said yoke for forcing it against said shell, to thereby secure said shell in place within said opening; an insulating member secured in place within said shell; and electrodes carried one by said insulating member and the other by said shell or casing.
2. In combination with a cylinder wall having a tapered opening therein and the periphery of which opening is smooth throughout its entire extent; a hollow, smooth and unthreaded metallic shell or casing conical in form and fitting within said opening; a yoke engaging the upper end of said shell to hold it in place within said opening; and an insulating member located within said shell or casing; said shell having a holding flange integral with the upper end thereof and turned inward and into permanent holding engagement with said insulator; and the peripheral surface of said shell having a metallic coating thereon.
3. In combination with a cylinder wall having a tapered opening therein; a hollow metallic shell or casing tapering in form and fitting within said opening, the cooperating surfaces of said shell and the interior of said opening being smooth throughout their entire extent, and the shell being as long as the opening so as to fit therein throughout the entire extent of the inner peripheral wall thereof; means for holding said shell in place within said opening; an insulating member held in place within said shell or casing; and a thin film of metal upon the exterior peripheral surface of said shell throughout the area of contact between the same and the inner peripheral wall of said opening.
4. A spark plug comprising a hollow metallic shell or casing tapering in form and smooth throughout its conical part, and which casing has an electrode at its inner end, and an inturned holding flange formed integrally therewith at its upper end; an insulating member permanently held in place in said shell by the holding flange aforesaid; and an electrode carried by said insulating member and arranged in sparking relation to said first mentioned electrode.

In testimony whereof I affix my signature.
